[57] CLAIM

The ornamental design for a roast spit, as shown and described:

DESCRIPTION

FIG. 1 is a front elevational view of a roast spit showing my new design;

FIG. 2 is a right end elevational view thereof;

FIG. 3 is a back elevational view thereof;

FIG. 4 is a left end elevational view thereof;

FIG. 5 is a top plan view thereof; and

FIG. 6 is a bottom plan view thereof.

The broken line disclosure shown in all views is for illustrative purposes only and forms no part of the claimed design.
